UNITED STATES PATENT OFFICE

93,449

DESIGN FOR A RADIOCABINET

Walter O. Brown, Detroit, Mich.

Application July 21, 1934, Serial No. 52,662

Term of patent 14 years

To all whom it may concern:

Be it known that I, WALTER O. BROWN, a subject of the King of Great Britain, residing at Detroit, in the county of Wayne and State of Michigan, have invented a new, original, and ornamental Design for a Radio Cabinet, of which the following is a specification, reference being had to the accompanying drawing forming a part thereof.

In the drawing:

Fig. 1 is a front perspective view of a radio cabinet embodying my invention.

Fig. 2 is a side elevation thereof.

I claim:

The ornamental design for a radio cabinet as shown.

WALTER O. BROWN.
